UNITED STATES PATENT OFFICE.

CAID H. PECK, OF WAVERLY, NEW YORK, ASSIGNOR TO INGERSOLL-RAND COMPANY, OF JERSEY CITY, NEW JERSEY, A CORPORATION OF NEW JERSEY.

PNEUMATIC HAMMER.

Application filed August 3, 1921. Serial No. 489,516.

To all whom it may concern:

Be it known that I, CAID H. PECK, a citizen of the United States, a resident of Waverly, county of Tioga, and State of New York, have invented a certain Pneumatic Hammer, of which the following is a specification, accompanied by drawings.

This invention relates to pneumatic tools, but more particularly to riveting hammers and the like, having a cylinder, a reciprocating piston, which constitutes the hammer and a fluid actuated distributing valve.

The objects of the invention are to improve upon and increase the efficiency of a valve for such pneumatic hammers, sometimes called a central type valve, of hollow cylindrical form, movable in axial alignment with the cylinder preferably in a valve casing located at the rearward end of the cylinder, the valve having a bore equal in diameter to the bore of the cylinder, to permit the piston to pass through the valve on its rearward stroke.

To these and other ends which will appear, the invention consists of the features of construction, arrangement of parts and combinations of elements substantially as hereinafter fully described and claimed in this specification and shown in the accompanying drawings, in which—

Figure 1 is a diagrammatic longitudinal sectional elevation of a pneumatic hammer embodying the invention, the ports and passages all being shown in one plane for simplicity of illustration and description.

Figure 2 is a similar view on a larger scale, with portions forming no part of the invention broken away and the valve shown in its forward position with the piston about to complete its rearward stroke and start on its forward stroke, and

Figure 3 is a similar view with the valve partly in longitudinal section and partly broken away and in its rearward position with the piston having completed its forward stroke and starting on its rearward stroke.

Referring to the drawings, the pneumatic hammer comprises the cylinder A having a bore B in which the pneumatic hammer piston C is adapted to reciprocate and impart blows of impact to a rivet set D or other tool removably held within the forward end of the cylinder as by means of the rivet set clip E of any suitable character. A

suitable handle F secured to the cylinder as by means of the bolts G forms the back head of the machine and pressure fluid from the inlet H controlled by the hand operated valve J of any suitable form, is supplied to the machine through the main supply passage K.

In this instance a valve block L and a cap piece O fitted together form a valve casing removably held within the rearward end of the cylinder by the handle or back end F. A hollow cylindrical fluid actuated differential distribution valve P is slidable longitudinally within the valve casing in axial alignment with the cylinder A and is formed with a bore Q equal in diameter to the bore of the cylinder, to permit the piston C to pass through the valve on its rearward stroke. The valve P controls the admission and exhaust of motive fluid from both ends of the cylinder by means of suitable ports and passages in the cylinder, the head block L and the cap piece O. The valve is preferably imperforate, having solid walls as shown and all the distributing ports and passages are entirely outside of and external to the valve itself, which enables the valve to be made stronger and of more rugged construction and better able to withstand the hard and continuous usage to which the machine is subjected.

The surface of the rearward end of the valve forms a single forwardly acting pressure area R preferably beveled as shown in the drawings and larger than the pressure surface of the forward beveled end S of the valve. The valve is also provided with an intermediate head T having a surface U forming a rearwardly acting intermittently supplied pressure area, and a neck V located forwardly of the head T, for controlling the supply to the forward end of the cylinder through the combined supply and exhaust passage W in the cylinder, communicating with the forward end of the cylinder through the port X, and also for controlling the exhaust from both ends of the cylinder through the exhaust passage Y preferably protected by a suitable exhaust deflector Z.

Means are provided for holding the valve P in forward position indicated in Figure 2, by live pressure fluid on the larger forwardly acting pressure area R of the valve, as the piston C travels on its forward stroke, and for this purpose with the parts in the

position indicated in Figure 2, actuating pressure fluid is admitted from the supply passage K to the groove *a* in the handle or back head F, thence through the supply passage *b* in the valve block L to the groove *c* in the valve block and thence to the rearward chamber *d* in the valve block, which chamber, as shown, is also constantly open to live motive fluid through the small ports *x* and *y* leading from the main supply. The live pressure fluid which actuates the piston forwardly, acting on the larger pressure surface R of the valve, will hold the valve in forward position even after the piston in its forward travel has passed the forward end S of the valve, thus subjecting that end of the valve to pressure fluid. As the piston C travels forwardly, the forward end of the cylinder exhausts through the port X, passage W, port *e* in the cap piece O, through the groove *f* around the valve neck V and through the port *g* to the atmosphere through the exhaust passage Y.

Means are provided for actuating the valve P rearwardly by live pressure fluid exerted on the rearwardly acting intermittently supplied pressure area U of the intermediate head T, as the piston completes its forward stroke. When the piston has almost delivered its forward or power stroke, the rearward end of the piston will have uncovered a timing port *h* in the bore of the cylinder communicating by means of a passage *j* in the cylinder wall with a timing port *k* opening into the head chamber *o* in the valve block L, in which the valve head T reciprocates. The cap piece O is preferably provided with a recess or groove *p* to uncover the timing port *h* and permit said port *k* to be located at the forward end of the head chamber *o* when the block L and cap piece O are assembled in the cylinder. The uncovering of the timing port *h* in the forward travel of the piston admits pressure fluid driving the piston, through passage *j* and timing port *k*, to the surface U of the valve head T, which will start the rearward movement of the valve. In order, however, to obtain a quick acting valve, means are provided for supplying additional live air pressure to the surface U of the valve, and for this purpose a port *q*, leading to the head chamber *o*, when uncovered by the valve T in its rearward travel, admits live air pressure to the surface U, directly from the main supply *b* through the passage *r*. Any pressure in the head chamber *o* behind the valve head T is relieved through the port *s* and passages *t* and *u* communicating with the main exhaust. The port *s* is preferably located a short distance forwardly of the rear end of the head chamber in order to trap air and form a cushion behind the valve head T in its rearward travel.

When the valve has been shifted rearwardly to the position indicated in Figure 3, the piston has delivered its power stroke and pressure fluid for returning the piston is admitted to the forward end of the cylinder from the passage *r* in the valve block L to passage *v* in the cap piece O, through the port *w* in the cap piece, past the neck V of the valve, through the groove *f*, and thence through the passage W and port X to the forward end of the cylinder for the return stroke. As the piston travels rearwardly, fluid is exhausted from the cylinder through the port *g* and the exhaust port Y to atmosphere. Pressure against the face U of the valve head T within the head chamber *o* is also released through the timing port *h*, passage *j*, and timing port *h'* when uncovered which communicates with that portion of the cylinder under reduced pressure. Two timing ports *h* and *h'* both communicating with the passage *j*, are preferably provided one forwardly of the other although one only could be used if desired.

After the rearward end of the piston has passed and covered the exhaust port *g*, compression of pressure fluid builds up pressure in the chamber *d* rearwardly of the valve P, and the valve is actuated forwardly when sufficient compression pressure due to live pressure fluid and to compression of the fluid by the piston rearwardly of the valve acts on the larger rearward pressure area R of the valve, which occurs as the piston completes its rearward stroke. The valve P then assumes the position indicated in Figure 2, and the cycle is repeated. It is evident that with the parts in the position indicated in Figure 2, there will be no pressure on the rearwardly acting surface U of the valve head T since pressure has been relieved from this surface through the timing port *h*, passage *j*, and timing ports *h* and *h'*, which are again open to atmosphere through the cylinder, the port X, passage W, the port *e*, groove *f* and exhaust ports *g* and Y. The valve will thus be held in its forward position by live air pressure on the forwardly acting rear surface R of the valve.

The cushion formed by pressure fluid trapped in the chamber *d* in the rearward end of the valve block L, prevents the rearward end of the piston from striking the valve block on the return stroke. The small ports *x* and *y* which, as stated, are preferably provided leading to the chamber *d* from the main supply, insure that this chamber is constantly open to live air pressure. Furthermore, if the hammer is to be used upside down, for instance, for driving rivets, the piston C will drop down against the back end S of the valve block L, but the constant air supply through the small port *x* will raise the valve P, uncovering the groove *c*,

and the live air pressure through the small port *y* will raise the piston above the face 3, of the chamber *d*, thus admitting pressure fluid behind the piston into the chamber *d* 5 for the power stroke.

I claim:

1. A pneumatic hammer comprising a cylinder and piston, a hollow imperforate valve located within the rearward end of the cylinder, through which valve the piston passes, a chamber rearward of the valve constantly open to live pressure fluid, the rearward end of the valve having a forwardly acting pressure area larger than the forward end of the valve, said valve being provided with an intermediate head having a rearwardly acting pressure area, and having a neck located forwardly of said head controlling the supply of pressure fluid to the front end of the cylinder, and the exhaust from both ends of the cylinder, means for holding the valve in forward position by live pressure fluid exerted on the said larger forwardly acting pressure area of the valve, means for intermittently subjecting the said rearwardly acting pressure area of the intermediate head to live pressure fluid for actuating the valve rearwardly, and means for actuating the valve forwardly by pressure on the larger forwardly acting pressure area of the valve due to live pressure fluid and to compression of fluid by the piston in said chamber rearwardly of the valve as the piston completes its rearward stroke.

2. A pneumatic hammer comprising a cylinder and piston, a hollow imperforate valve located within the rearward end of the cylinder, through which valve the piston passes, a chamber rearward of the valve constantly open to live pressure fluid, the rearward end of the valve having a forwardly acting pressure area larger than the forward end of the valve, said valve being provided with an intermediate head having a rearwardly acting pressure area, and also having a neck located forwardly of said head controlling the supply of pressure fluid to the front end of the cylinder and the exhaust from both ends of the cylinder, means for holding the valve in forward position by live pressure fluid exerted on the said larger forwardly acting pressure area of the valve, means for intermittently subjecting the said rearwardly acting pressure area of the intermediate head to live pressure fluid from the cylinder to start the valve and to additional live pressure fluid direct from the supply in order to throw the valve more quickly to its rearward position, and means for actuating the valve forwardly by pressure on the larger forwardly acting pressure area of the valve due to live pressure fluid and to compression of fluid by the piston in said chamber rearwardly of

the valve as the piston completes its forward stroke.

3. A pneumatic hammer comprising a cylinder and piston, a solid imperforate valve located within the rearward end of the cylinder, through which valve the piston passes, a chamber rearward of the valve constantly open to live pressure fluid, the rearward end of the valve having a forwardly acting pressure area larger than the forward end of the valve, said valve being provided with an intermediate head having a rearwardly acting pressure area, and also a rearward surface open to atmosphere for a portion of the forward and rearward travel of the valve but closed to atmosphere for the latter portion of the rearward travel of the valve in order to cushion the valve, said valve also having a neck located forwardly of the said head controlling the supply of motive fluid to the front end of the cylinder and the exhaust from both ends of the cylinder, means for holding the valve in forward position by live pressure fluid exerted on the said larger forwardly acting pressure area of the valve, means for intermittently subjecting the said rearwardly acting pressure area of said intermediate head to live pressure fluid for actuating the valve rearwardly, and means for actuating the valve forwardly by pressure on the larger forwardly acting pressure area of the valve due to live pressure fluid and to compression of fluid by the piston in said chamber rearwardly of the valve as the piston completes its rearward stroke.

4. A pneumatic hammer comprising a cylinder and piston, a hollow imperforate valve located within the rearward end of the cylinder through which valve the piston passes, a chamber rearward of the valve constantly open to live pressure fluid, the rearward end of the valve having a forwardly acting pressure area larger than the forward end of the valve, said valve being provided with an intermediate head having a rearwardly acting pressure area, and also a surface open to atmosphere for a portion of the forward and rearward travel of the valve but closed to atmosphere for the latter portion of the rearward travel of the valve in order to cushion the valve, said valve also having a neck located forwardly of the said head controlling the supply of motive fluid to the front end of the cylinder and the exhaust from both ends of the cylinder, means for holding the valve in forward position by live pressure fluid exerted on the said larger forwardly acting pressure area of the valve, means for intermittently subjecting the rearwardly acting pressure area of said intermediate head to live pressure fluid from the cylinder to start the valve and to additional live pressure fluid direct from the supply in order to throw the valve more

quickly to its rearward position, and means for actuating the valve forwardly by pressure of the larger forwardly acting pressure area of the valve due to live pressure fluid and to compression of fluid by the piston in said chamber rearwardly of the valve as the piston completes its rearward stroke.

5. A pneumatic hammer comprising a cylinder and piston, a hollow imperforate valve 10 located within the rearward end of the cylinder, through which valve the piston passes, a chamber rearward of the valve constantly open to live pressure fluid, the rearward end of the valve having a forwardly acting pressure area larger than the forward end of the valve, said valve being provided with an intermediate head having a rearwardly acting pressure area and a neck located forwardly of said head controlling the supply 15 of pressure fluid to the front end of the cylinder and the exhaust from both ends of the cylinder, and admission port at the rearward end of the cylinder, a head chamber adjacent the valve communicating with the 20 main supply and with the atmosphere, said intermediate head operating in said head

chamber to control said communication between the head chamber and the supply and the atmosphere, passages controlled by the piston affording communication between the 30 said head chamber and the bore of the cylinder, means for holding the valve in forward position by live pressure fluid exerted on the said larger forwardly acting pressure area of the valve, the valve being actuated 35 rearwardly as the piston completes its forward stroke, by intermittently subjecting the rearwardly acting pressure area of said intermediate head to live pressure fluid from the cylinder to start the valve and to additional live pressure fluid direct from the supply in order to throw the valve more quickly to its rearward position, and means for actuating the valve forwardly by pressure on the larger forwardly acting pressure area of the valve due to live pressure fluid and to compression of fluid by the piston in said chamber rearwardly of the valve as the piston completes its rearward stroke.

40 In testimony whereof I have signed this 45 specification.

CAID H. PECK.
